UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

INKING MECHANISM FOR PRINTING PRESSES.

Application filed May 29, 1926. Serial No. 112,573.

This invention is a novel improvement in inking mechanism for printing presses, and has particular reference to means for mounting form and distributing rollers to regulate the pressure and to compensate for shrinkage of the rolls.

The accompanying drawings illustrate one practical embodiment of the invention, and I will explain the invention with reference thereto to enable others to adopt and use the same. In the claims the novel features of construction and combinations of parts for which protection is desired are summarized.

15 In said drawings:

Figure 1 is a top plan view of a portion of the inking mechanism of a printing press showing my improved ink-roller supports.

Fig. 2 is an enlarged side view of one of 20 the roller supports.

Fig. 3 is an end view of Fig. 2.

In the drawings I have shown the invention as used in connection with an ordinary inking mechanism having an ink distributing drum D mounted in framing F of any suitable construction. Cooperating with this drum is a distributing roller R which is journaled in adjustable supports, each comprising a supporting member 1 and a complementary member 1^b hinged to the member 1 at 1^a. Member 1^b can be securely locked against the member 1 so as to enclose and support the roller journal. As shown a screw 2 is pivoted at 2^a to a lug on the upper side of member 1, and is adapted to be engaged with a bifurcated lug 1^c on the upper side of member 1^b. When the member 1^b is closed against the member 1, as in Fig. 2, the bolt 2 is dropped into engagement 35 with the lug 1^c, and clamped thereagainst by a wing-nut 2^b as indicated in the drawings.

Member 1^b has an arm 1^h by which it can be raised or lowered, and has a dog or tooth 45 1^d on its lower side by which the opening or lowering movement of the member 1^b is limited.

The roller supports are adjustably mounted on the frame F by means of rearwardly extending arms 1^e on members 1 engaging slots f in the frame. Each arm 1^e has an elongated slot 1^f (indicated in dotted lines in Fig. 2) through which passes a bolt 3 which is tapped into the frame F. The member 1 also has a slotted lug 1^g on its up-

per side which is rotatably engaged with a screw 4 tapped into the frame F above the arm 1^e; said screw having a head 4^a and a collar 4^b, between which the lug 1^g closely fits.

The parts as thus far described are, or may be, of well known construction.

It is necessary to have the roller R adjustable, so as to cause it to bear on the ink drum or form (as the case may be) with more or less pressure, and to take up shrinkage of the ink roll. This adjustment is commonly made by adjusting arm 1^e in the slot in the frame by means of screw 4 and when adjusted to the satisfaction of the operator the roll support is clamped firmly in place by tightening bolt 3. So far this is common construction and practice. It is obvious that such adjustment requires three operations for each support; first arm 1^e must be unclamped by loosening bolt 3; second, the socket must be adjusted by means of screw 4; and third, the socket must be clamped by tightening the bolt 3.

The object of the present invention is to appreciably shorten the time necessary to adjust these rollers, and this is accomplished by a very simple but practically important improvement in the construction.

In my invention the bolt 3 is elongated, and a stiff spring 5 which may be of any suitable kind, (being shown as a metal spring,) is interposed between the shank 1^e and the head 3^a of the bolt 3. This spring must be stiff enough to firmly hold the socket arm against the frame by frictional contact and to resist displacement by the normal pressure on the ink roll, and yet be yielding enough to allow the screw 4 to be operated for adjustment.

Washers 3^b-3^c are preferably used on bolt 3 to "square" or "center" the spring 5 so it will press evenly on the arm 1^e and the head of the bolt 3.

With this simple improvement the setting of each roll support requires only one operation instead of three as outlined above.

There are ordinarily twenty-eight ink roller sockets to be adjusted on every sixteen page printing section. In an octuple press consisting of four sections obviously there are 112 such roller sockets. Each such roller socket heretofore has required three operations to adjust it but by my invention only one is required, the amount of work and

labor saved will be readily appreciated—
f. i., to adjust all the rollers in an ordinary
16 page press with the old style supports 84
operations are required. The same press
5 equipped with my improvement could have
all the rollers adjusted in twenty-eight oper-
ations. The placing of this improvement on
the roller socket means that 112 operations
instead of 336 operations are necessary in
10 making the adjustment for the full comple-
ment of rollers on an octuple press.

In order to remove the ink roller the
thumb nut 2^b is unscrewed and the I-bolt 2
15 with thumb nut lifted clear of the slot in
lug 1^c—then the cap member 1^b can be
swung downward on its hinge until the lug
1^a strikes the lower edge of member 1. This
lug 1^a is positioned to stop member 1^b from
20 further revolving around its hinge, and the
roller R can then be readily removed or re-
placed.

I claim:—

1. In inking mechanism of the character
specified including a frame, an ink drum,
25 and coacting distributing rollers; inking
roller supports adjustably mounted on the
frame; friction means for normally holding
the supports in any adjusted position; and
means for adjusting said supports relative
30 to the frame without changing the adjust-
ment of said friction means.

2. In inking mechanism of the character

specified, including a frame, an ink drum
and coacting distributing roller; of inking
35 roller supports each having an arm engag-
ing the frame, a bolt tapped into the frame
and rotatably engaged with the support to
adjust the latter relative to the frame; ad-
justable resilient friction means engaging
the said arm and normally holding the latter 40
in any adjusted position; and means at-
tached to the frame and engaging said sup-
port for adjusting it relative to the frame
without changing the adjustment of said
friction means.

3. In inking mechanism of the character
specified; including a frame, a drum and a
coacting distributing roller; inking roll sup-
ports each comprising a supporting member
50 having a slotted arm, a cap member con-
nected with the supporting member, a bolt
transfixing the slot in said arm; resilient
friction means interposed between the head
of the bolt and said arm to normally hold
55 the support in any adjusted position, and a
bolt tapped into the frame and rotatably en-
gaged with the supporting member to adjust
the latter relative to the frame without
changing the adjustment of said friction
60 means.

In testimony that I claim the foregoing as
my own, I affix my signature.

HENRY F. BECHMAN.
